UNITED STATES PATENT OFFICE.

LOUIS N. D. WILLIAMS, OF OGONTZ, PENNSYLVANIA, ASSIGNOR OF ONE-HALF TO ROBERT W. SCOTT, OF PHILADELPHIA, PENNSYLVANIA.

KNITTED FABRIC.

No. 853,687.

Specification of Letters Patent.

Patented May 14, 1907.

Application filed April 21, 1903. Serial No. 153,709.

To all whom it may concern:

Be it known that I, LOUIS N. D. WILLIAMS, a citizen of the United States, residing in Ogontz, Montgomery county, Pennsylvania, have invented certain Improvements in Knitted Fabric, of which the following is a specification.

My invention consists of certain improvements in the knitted fabric forming the subject of Letters Patent No. 709,734 issued September 23rd 1902 to Robert W. Scott and myself, as assignees of David C. Bellis, one object of my present invention being to permit the use of heavier yarn in the backing web than in the face web, in such a way as will render the fabric preferable, in many cases, to the patented fabric having such coarse back web, a further object being to render available for the heavier web material not available in the fabric as originally made.

These objects I attain in the manner hereinafter set forth reference being had to the accompanying drawing, in which—

Figure 1, is an exaggerated sectional view of a piece of fabric made in accordance with my invention; and Fig. 2, is an exaggerated face view of said fabric.

The fabric is similar to that formerly patented in that it consists of two single webs, one overlying the other, these webs being united together at any desired points by causing yarn of one web to engage with the other web, such engagement being in the form of a loop or stitch, thus in Fig. 1 of the drawing, 1 represents a face web, 2 a backing web, and 3 uniting loops of the face web carried into the back web and interlooped therewith so as to tie the two webs together.

The present fabric is akin to that shown in Fig. 7 of the drawing of the former patent in having a backing web composed of coarser yarn than the face web, but it differs from the former fabric in having, in the back web, both fewer wales of stitches and fewer courses of stitches than are contained in the face web, the fabric shown in the drawing having just one-half as many wales and courses in the back web as there are in the face web.

A fabric such as that shown in Fig. 7 of the Bellis patent is open to either of two objec-

tions, namely: the stretching of the stitches of the fine face web if the heavy rear web is the dominating one, or the bulging or pouching of the rear web between the tying points if the fine face web is the dominating one, since it is evident that a certain number of courses and wales of stitches knitted with a heavy yarn will occupy a greater area than that number of courses and wales of stitches knitted with a fine yarn, unless the latter stitches are stretched or spread, thereby producing a face web of open texture, while if, on the other hand, the face web is knitted of close texture the greater area of the rear web between successive tying points will naturally result in a bulge or pouch in said rear web.

Difficulty will furthermore be experienced in "knocking over" the stitches of the coarser yarn unless web holders are used in connection with the needles for knitting the same, because of the failure of the take-up to impart proper tension to the longer and coarser web.

By lessening the number of wales and courses of stitches in the back web, excess in area of said web is prevented, the web can be subjected to proper tension, coarser needles can be employed for engagement with the coarser yarn of which the back web is composed, a lesser amount of said yarn will be needed than before, and said yarn can be composed of material not otherwise available, for instance, it may be composed of linen, which, owing to the fact that it is much less flexible than cotton or wool, cannot be knitted on a fine gage machine, although the use of linen in knitted garments intended for underwear is, in many cases, desirable.

For the purpose of knitting my improved fabric I prefer to employ a machine resembling a rib knitting machine and having a knitting cylinder and dial with cylinder cam box and dial cam plate as usual, but having independent yarn feeds for the needles of the cylinder and dial, half as many needle grooves in the dial as there are in the cylinder, and half as many yarn feeds and cams for the dial needles as there are for the cylinder needles, such machine forming the subject of a separate application filed of even date herewith Serial No. 153,710.

I have shown in the drawing but one method of uniting the face and back webs of the fabric, but it is evident that my present invention is not limited thereto but may be carried out in connection with any of the different styles of fabric shown in the above mentioned patent No. 709,734, or in other ways which will suggest themselves to those skilled in the art.

10. The good results of my invention may, in a measure, be attained by simply diminishing the number of courses of stitches in the backing fabric as compared with the number of courses in the face fabric, or even 15 by diminishing the number of wales of stitches instead of by lessening the number of both courses and wales, although the latter construction is preferred.

In a fleece lined fabric, the fleece produced by brushing the yarns of the back web serves to cover the back of the fabric and thus disguises the open character of said back web.

In my Letters Patent No. 709,840, dated 25 September 23rd, 1902, long or tuck stitches were drawn in certain portions of the face web, but throughout the greater portion of said face web, the latter had as many courses of stitches as the back web, hence said patented fabric differed materially from the 30 present fabric.

Having thus described my invention, I claim and desire to secure by Letters Patent:—

1. A knitted fabric comprising two webs 35 one overlying the other and united at intervals by yarn of one web engaging the other web, one web being composed of a coarser yarn than the other web and having a less number of courses of stitches than said other web, substantially as specified.

2. A knitted fabric comprising two webs one overlying the other and united at intervals by yarn of one web engaging the other web, one web being composed of a coarser 45 yarn than the other web and having a less number of wales of stitches than said other web, substantially as specified.

3. A knitted fabric comprising two webs 50 one overlying the other and united at intervals by yarn of one web engaging the other web, one web being composed of a coarser yarn than the other web and having a less number of wales and courses of stitches than said other web, substantially as specified. 55

In testimony whereof, I have signed my name to this specification, in the presence of two subscribing witnesses,

LOUIS N. D. WILLIAMS.
